BLOWPIPES

Charles Frederick Steventon, London, England, assignor to The British Oxygen Company Limited, a British company

Application November 14, 1955, Serial No. 546,754

3 Claims. (Cl. 137—271)

This invention relates to blowpipes and more particularly to blowpipes for cutting metal by means of a jet of oxidising gas.

Such blowpipes normally comprise a nozzle unit, conduits supplying said nozzle unit with fuel gas for a heating flame and oxidising gas for cutting metal which has been heated, and a hollow body portion surrounding said conduits. The nozzle unit usually extends at an angle, e.g. a right angle, to the body portion, and the blowpipe is supported and positioned by the operator holding the body portion by hand. The supply of fuel gas is controlled by fine adjustment screw valves which are attached to the body portion and which remain set after adjustment. The oxidising gas is, however, applied intermittently and is most conveniently controlled by a valve which is adjusted by means of a lever pivotally mounted on the body portion.

The lever is usually mounted adjacent one end of the body portion and provided with a handle extending generally parallel to the axis of the body portion, and the lever is operated by gripping movement between the palm and fingers of the operator's hand. This arrangement has the advantage that the operator can control the lever with the hand supporting the blowpipe.

Previously known blowpipes have the lever mounted in one or other of four positions, namely a forward overslung position with the lever pivoted at the front end of the body portion of the blowpipe, that is, the end adjacent the nozzle unit, and the handle of the lever extending rearwards and above the said body portion, a rear overslung position with the lever pivoted at the rear end of the body portion and the handle extending forwards and above the said body portion, a forward underslung position and a rear underslung position.

Blowpipe operators generally have their own personal preferences regarding the relative positions of the lever and the body portion of a blowpipe, and as the effect in operating the lever is fatiguing over a prolonged period of time, it is desirable and has been usual to provide an operator with a blowpipe which suits his own particular preference.

It has already been proposed to provide a blowpipe having a lever which may be mounted in either the forward overslung or the forward underslung positions and it has also been proposed to provide a blowpipe having a lever which may be mounted in either the rear overslung or the rear underslung positions.

The object of the present invention however is to provide a blowpipe having a lever which may be readily mounted selectively in any of the above mentioned four positions.

According to the invention a blowpipe for cutting metal by means of a jet of oxidising gas comprises a body portion, a valve for controlling the supply of oxidising gas, a sliding control within the body portion for opening and closing said valve, and a lever including a handle and a pivot lug angularly disposed with regard to said handle for moving said sliding control, the said body portion

2

having forward and rear transverse apertures for the reception of the pivot lug of the lever inserted from either one of the two ends of either of said apertures, and the said lug having two pivot points, spaced along its length

5 and adapted to be selectively associated with one of four separate pivot axes, two in each of said apertures, the two pivot axes in each aperture being disposed one on each side of the longitudinal axis of said sliding control and the arrangement being such that the handle of the lever extends forwards or rearwards when the lug is inserted into either end of the rear or forward apertures respectively and that movement of the handle towards the body portion about the appropriate one of its two spaced pivots, with the lever in any one of the four alternative positions, effects operational engagement between the said lug and the said sliding control always to move the latter in the direction to open the valve.

An embodiment of the invention will now be described by way of example with reference to the accompanying drawings in which:

Figure 1 is a side view of a blowpipe according to the invention, having the lever controlling the supply of oxidising gas in the rear overslung position;

Figure 2 is a sectional view along the line X—X of Figure 1 showing the lever in the rear overslung or underslung positions, the fine adjustment valves for the oxidising gas and fuel gas being omitted;

Figure 3 is a sectional view along the line Y—Y of Figure 2 but showing the lever in the forward overslung position;

Figure 4 is a similar view to Figure 3 but showing the lever in the rear overslung position; and

Figure 5 is a cross-sectional view taken along the line Z—Z of Figure 3.

35 Referring now to Figure 1 the blowpipe comprises a nozzle unit 10, conduits 11 and 12 for supplying fuel gas and oxidising gas (to support combustion of the fuel gas) respectively to the nozzle, a separate conduit 13 for supplying the cutting stream of oxidising gas to the nozzle, a valve block 14 on which the conduits 11, 12, 13 are mounted at their rear ends and a hollow cylindrical body portion 15 enclosing the rear end portion of the conduits 11, 12, 13 and the valve block 14.

40 The valve block 14 has inlet connections, 16 and 17 for connection to supplies of fuel gas and oxidising gas respectively and fine adjustment valves of which only the control knobs 18 and 19 are shown, for controlling the flow of fuel gas and oxidising gas through the conduits 11 and 12 respectively.

45 50 The valve block 14 is also provided with valve means controlling the flow of cutting oxidising gas from the inlet 17 to the conduit 13. As shown in Figure 2, this valve means comprises a closure member 20 biassed against a co-operating valve seat 21 formed within the

55 valve block 14, by a coil spring 22. The closure member 20 and spring 22 are housed within a chamber 23 formed in the rear end of the valve block 14 and closed by a screw 24 against which one end of the spring 22 abuts. The valve is positioned with its axis lying parallel to the axis of the body portion but offset therefrom as shown in Figure 2, the closure member 20 being biassed in the forward direction (that is towards the nozzle) by the spring 22. Adjustment of the valve means is effected by control means slidably mounted within the body portion 15 for movement in the direction of the axis of the valve means.

70 65 The control means comprises a rod 25 adapted to slide within an aperture 26 formed within a forward block 27 mounted on the conduits 11, 12, 13 and within the body portion 15. This rod 25 is provided with a screw-threaded portion 28 on which are mounted a pair of lock nuts 29, 30. The rear end of the rod 25 is surrounded

by and slidable within a sleeve 31 abutting at its forward end against the lock nuts 29, 30 and closed at its rear end to form a plunger 32, the end of which abuts against the closure member 20. The sleeve 31 is slidable within an aperture in the valve block 14. The rod 25 is slotted at either end at 33 and 34 respectively and is provided with bores 35, 36 intersecting the slots 33 and 34 respectively at right angles. The purpose of these slots and bores will be described hereinafter.

The body portion 15 is provided with eight axially-extending slots 37 some of which are shown in Figures 1, 3 and 4, two of said slots being formed immediately above and below the forward slot 33 in the rod 25 and two more immediately above and below the rear slot 34 in the rod 25. The four remaining slots 37 are formed symmetrically in the body portion 15 with respect to the first four slots 37. Co-operating slots 49 are also provided in the valve block 14 and the forward block 27. The forward block 27 is also provided with four apertures 38 shown in Figure 5 suitable for mounting a pair of pivot pins 43 on either side of the slots 33 in the rod 25. The valve block 14 is provided with similar apertures not visible in the drawings for mounting the pivot pins on either side of the slot 34 in the rod 25.

An operating lever comprises a handle 39 and a U-shaped pivot lug projecting substantially at right angles from the handle. The arms 40 of the pivot lug are spaced apart at a distance equal to the distance between a pair of adjacent slots 37 on the top surface of the body portion 15, and each of the arms 40 is provided with a distal bearing 41 and a root bearing 42 for the reception of the pivot pins 43, the two bearings 41 and 42 being spaced apart along the length of the arm 40 by a distance between adjacent pivot pin mountings 38 in the forward block 27. In addition each arm 40 is provided with a slotted bearing 44, intermediate the bearings 41 and 42.

The operating lever may be mounted on the body portion 15 in any one of four positions, namely the forward overslung, the forward underslung, the rear overslung and the rear underslung position.

The operating lever mounted in the forward overslung position is illustrated in full lines in Figures 3 and 5. The lever is arranged with the handle 39 pointing to the rear, the two arms 40 of the lug inserted through the pair of slots 37 at the forward end of the top surface of the body portion 15 and the arm of the lug adjacent to the control means passing through the forward slot 33 in the rod 25. A pin 45 is mounted in the forward bore 35 in the rod 25 passing through the bearing 44 in the arm 40, and the lever is pivoted to the forward block 27 by the pair of pins 43 journaled in the distal bearings 41 of the arms 40 of the lug, the pins 43 being supported in the appropriate apertures 38 in the forward block 27. The pivot pins 43 are retained in the apertures 38 by the body portion 15 as indicated in Figure 5, access to the pivot pins 43, rod 25, etc. being obtained by sliding the forward block 27 out of the body portion 15. Upon movement of the lever towards the body portion 15, the arm 40 of the lug passing through the slot 33 in the rod 25 causes the pin 45 to drive the rod 25 in a rearward direction. This movement in turn causes the lock nuts 29, 30 to drive the sleeve 31 in the same direction so that the plunger 32 opens the closure member 20 against the action of the spring 22. In order to limit the play of the lever before it causes the valve to open, the lock nuts 29, 30 are adjusted on the threaded portion 28 of the rod 25 so that the end of the plunger 32 just touches the closure member 20 when the lever is at its maximum distance from the body portion 15.

The lever in the forward underslung position is shown in dotted lines in Figure 3. In this position the lever is arranged with its handle 39 extending to the rear and the two arms 40 of the lug inserted through the pair of slots 37 at the forward end of the bottom surface of the body portion 15. The lever is pivoted by pins 43

journaled in the distal bearings 41 of the arms 40, the pins 43 being supported in the appropriate apertures 38 in the forward block 27. Movement of the handle 39 towards the body portion 15 effects rearward motion of the closure member 20, as already described with respect to the operation of the lever in the forward overslung position.

The lever mounted in the rear overslung position is shown in full lines and in the rear underslung position in dot and dash lines in Figure 4. The mounting and operation of the lever is the same as for the two corresponding forward positions with the exception that the pins 43 are journaled in the root bearings 42 of the arms 40 of the lever lug, in order to effect rearward motion of the rod 25. The valve block 14 may be slid out of the body portion 15 to allow access to the pivot pins 43.

Since in the forward overslung position, the pressure forcing the lever towards the body portion 15 to open the oxidising gas valve means is normally exerted by the thumb of the operator, extended depression of the lever to the fully operated position may be very tiring and means are therefore provided for locking the lever in the fully operated position, that is with the valve means fully open. These means comprise a member 46 slidably mounted upon the handle 39 and a finger 47 integral therewith and extending beneath and in the same direction as the free end of the handle 39. When the lever is in the fully operated position the member 46 is moved along the handle until the finger 47 engages in a pocket 48 mounted on the upper surface of the body portion 15.

I claim:

1. In a blowpipe having a body portion providing a hand grip, a valve block having a valve chamber provided with a valve seat, a closure member movable in said valve chamber and having a portion co-operating with said valve seat, an elongated control rod for operating said closure member and reversible means for operating said control rod, the combination of means mounting said control rod in said body portion for longitudinal sliding movement to operate said closure member, said control rod having a diametrical through slot adjacent each end thereof and a pivot pin hole intersecting each slot transversely, and said body portion having directly opposite openings at each end thereof in register with said through slots in the control rod and also having two axis pin mounting holes transverse to said openings at each end thereof and disposed one on each side of the control rod, a hand lever having a lug part extending through one of said openings in the body portion and through a slot in the control rod, said lug part having a pivot pin slot therein for registering with said pivot pin mounting hole in the control rod and an axis pin hole on each side of said pivot pin hole for registering with an axis pin mounting hole in the body, a removable axis pin for detachably pivoting said lug part to said body and a removable pivot pin for detachably pivoting said lug part to said control rod.

2. In a valve assembly having a valve block containing a valve chamber provided with a valve seat, a valve member movable in said chamber and having a portion co-operating with said valve seat, a manually graspable body part co-extensive with said valve block, and an elongated valve actuator and reversible means for operating said actuator, the combination of means slidably mounting said valve actuator within said body part, said actuator having a through slot adjacent each end and a transverse pivot pin mounting hole intersecting each slot transversely, and said body part having opposite openings at both ends which are in register with said slots at the respective ends of the actuator and also having axis pin mounting holes transverse to said openings and disposed at each side of said actuator, a hand lever, a lug on said hand lever which extends through one of the openings in said body part and through the slot in the valve actuator in register with said opening, said lug having a pivot pin slot for registering with one of the pivot pin mounting holes in the valve ac-

tuator and an axis pin hole on each side of said pivot pin hole for registering with an axis pin mounting hole in the body part, a removable pivot pin for detachably pivoting said lug part to said actuator at either end of the latter, and a removable axis pin for detachably pivoting said lug part to the body part for operation of the hand lever by manual squeezing pressure to move the actuator and operate the valve.

3. In a valve assembly according to claim 2, a sleeve 10 slidably mounted on said valve actuator and having one end abutting the valve, a screwthread on said actuator, and a lock nut adjustable on said screwthread and abutting

the other end of said sleeve, whereby the effective length of said valve actuator can be varied.
